UNITED STATES PATENT OFFICE.

WILLIAM C. LIEBERKNECHT, OF BISBEE, ARIZONA, ASSIGNOR TO MERGENTHALER LINOTYPE COMPANY, A CORPORATION OF NEW YORK.

SLUG-CASTING MACHINE.

1,193,275.

Specification of Letters Patent. Patented Aug. 1, 1916.

Application filed July 30, 1915. Serial No. 42,700.

To all whom it may concern:

Be it known that I, WILLIAM C. LIEBERKNECHT, a citizen of the United States, residing at Bisbee, in the county of Cochise 5 and State of Arizona, have invented certain new and useful Improvements in Slug-Casting Machines, of which the following is a specification, reference being had therein to the accompanying drawing.

10 My invention relates to typographical machines, such as linotype machines of the general organization represented in United States Letters Patent to O. Mergenthaler, No. 436532, wherein circulating matrices 15 are released from a magazine in the order in which their characters are to appear in print, and then assembled in line, the composed line transferred to the face of a mold, the mold filled with molten metal to form 20 a slug or linotype against the matrices which produce the type characters thereon, and the matrices thereafter returned through a distributing mechanism to the magazine from which they started. After 25 the slug is cast, it is delivered from the mold by an ejector which advances from the rear and moves it forwardly out of the mold and into a receiving galley.

It frequently happens that the slug is cast 30 with type characters extending only partly along its edge, the remaining portion being left plain. This is particularly true in tabular work and the like, wherein very short lines are employed. It has been found that 35 when printing from such slugs, the ink sometimes finds its way onto the plain portions and is impressed or carried on to the paper, resulting in the smearing or blurring of the printed matter.

40 My invention is intended to avoid the above objection and aims to produce a slug reduced or recessed beyond the type characters so that its plain portion will stand well below the printing surface when the slug is 45 assembled in a form, thus obviating any possibility of the ink becoming lodged upon the plain portion of the slug or of being transmitted to the paper. Specifically, I attain this object by providing one of the 50 mold liners with a longitudinally extending strip or member which projects into the mold slot at the front to partially fill the same and which will yield before the slug

as it is ejected from the mold. However, my invention is not restricted to the particular use above described, as it is apparent that there may be many instances where it will be desirable to cast recesses in the edges of the slugs, and without regard to whether they be formed with or without type characters. Thus, it may be desired in some cases to cast slugs with plain reduced or recessed portions to receive and support a cut or printing plate, while in other cases it may be desired to cast plain low quads to be inserted between the lines, which last result may be readily secured by simply extending the strip entirely across the mold slot.

I have herein shown my invention merely in preferred form and by way of example, 70 and obviously many changes and variations may be made therein which will be comprised within its spirit. I therefore desire it to be understood that I do not limit myself to any specific form or embodiment, 75 except in so far as such limitations are specified in the claims.

Referring to the drawings: Figure 1 is a perspective view of a portion of a linotype machine having my invention applied thereto; Fig. 2 is a longitudinal section taken through the mold and adjacent parts, and showing an assembled line of matrices in operative relation thereto; Fig. 3 is a section on the line 3-3 of Fig. 2; Fig. 4 is a 85 perspective view of my improved device detached; and Fig. 5 shows a slug produced in accordance with my invention.

The mold A is mounted upon the rotatable disk B, which presents it first in the casting position, where it is closed at the front by the composed line of matrices X confined between the clamping jaws G and G¹, as shown in Fig. 2, and subsequently carries it to the position shown in Fig. 1, 95 when the cast slug Z is removed from the mold by an ejector blade C, which advances from the rear and carries the slug forwardly between a pair of trimming knives D and delivers it to a receiving galley E, wherein 100 the slug is assembled along side a preceding slug or against the resistant E¹ by the stacking device F. The mold A comprises as usual the body portion A¹ and the cap A², constituting the side walls of the mold slot, 105 and the two intermediate fixed liners A³,

constituting its end walls. The left wall proper of the slot, however, is ordinarily constituted by the adjustable liner A⁴, which can be set in different longitudinal positions 5 therein to vary the length of the slugs. The parts so far described, except as hereinafter pointed out, are or may be of the regular construction.

In accordance with my invention, the adjustable liner A⁴ is provided at its front edge with a longitudinal strip or member A⁵ projecting beyond its inner or operative end so as to fill the mold slot partially at the front, it being noted that in the present 10 instance the strip does not extend throughout the full length of the slot but terminates therein to one side of those matrices having the formative cavities X¹, as clearly illustrated in Fig. 2. As a result of this construction, the slug Z is cast in the form shown in Fig. 5, having a type carrying surface Z² and a recess Z¹ located beyond it.

Since the slug Z is ejected forwardly from the mold, it is apparent that some provision should be made to remove the strip A⁵ from its outgoing path, and to this end the strip is pivotally connected to the liner A⁴, as at A⁶, so as to be swung outwardly by the slug as it is ejected, in the manner indicated in Fig. 1. After the slug passes the strip, it will ordinarily fall back into place, but in order to insure its return, there is provided a spring A⁸ located within a curved recess A⁸ of the liner and bearing 25 against the short arm A⁷ of the strip, the outer wall of the recess being concentric with the axis A⁶ so as to permit the movement of the arm during the swinging of the strip as just described.

Because of its attachment to the liner A⁴, the longitudinal position of the strip will be altered by the adjustment of the liner, so that a recess Z¹ will be formed in the slug whether the latter be of the length shown 40 in Fig. 5, or of the length shown in Fig. 1. However, such adjustment of the liner will not alter the extent of projection of the strip into the mold slot, and consequently the length of the recess Z¹ will not be varied. 45 Should that become desirable or necessary, the strip may be removed from the liner and replaced by another of different length, it being detachably connected to the liner for this purpose, as shown in Fig. 4. By 50 thus interchanging the strips, slugs may be produced with recesses of any desired length. If a strip projecting entirely across the mold slot be employed, a plain low slug or quad will result.

As previously stated, I have shown my invention merely in preferred form and by way of example, and it should be understood that many changes and variations may be made therein and in its mode of application 55 without departure from its scope. For

instance, it is not essential that the strip A⁵ should be carried by an adjustable liner, nor that it be used to produce a recess in the slug at its left end, since it would be practicable to connect the strip to a fixed 76 part of the mold, or to arrange it so as to produce a recess at the right end of the slug. Such modifications will readily suggest themselves to those skilled in the art.

Having thus described my invention, its 78 construction and mode of operation, what I claim and desire to secure by Letters Patent of the United States is as follows:

1. In a slug casting machine, the combination of slotted mold, a composed line arranged in operative relation thereto and comprising matrices formed with and without formative cavities, and means attached to the mold for partially filling the mold slot at the front and to one side of the matrices 80 having the formative cavities; whereby a slug is produced with a type carrying surface and a recess located beyond such surface.

2. A slotted mold provided with an attached strip or member projecting into the mold slot and only partially filling the same at the front, so as to produce a recess along the upper edge of the slug cast in the mold.

3. A mold comprising top and bottom portions and an intermediate end portion, the latter being provided with a strip or member projecting into and extending longitudinally of the mold slot and only partially filling the same at the front, so as to produce a recess 95 along the upper edge of the slug cast in the mold.

4. A slotted mold comprising top and bottom portions and an intermediate adjustable liner, the latter being provided with a strip or member projecting into and extending longitudinally of the mold slot and only partially filling the same at the front, so as to produce a recess along the upper edge of the slug cast in the mold.

5. A slotted mold provided with a strip or member projecting into and extending longitudinally of the mold slot and only partially filling the same at the front, the said member being movable from its operative position to permit the ejection of the slug from the mold.

6. A slotted mold comprising top and bottom portions and an intermediate end portion provided with a strip or member projecting into the mold slot and partially filling the same at the front, the said member being pivotally connected to the end portion so as to be displaced by the slug during its ejection from the mold.

7. A slotted mold comprising top and bottom portions and an intermediate end portion, the latter being provided with a pivotally connected strip or member projecting into the mold slot and partially filling the

same at the front, and also provided with a spring for holding the member yieldingly in its normal or operative position.

8. A slotted mold comprising top and bottom portions and an intermediate adjustable liner provided with a strip or member projecting into the mold slot and partially filling the same at the front, the said member being pivotally connected to the liner so as 10 to be displaced by the slug as it is ejected from the mold.

9. A mold liner provided at its front edge with a longitudinal strip or member projecting beyond its operative end, for the 15 purpose described.

10. The mold liner A⁴ provided with the longitudinal strip A⁵ projecting beyond its operative end, the said strip being pivotally connected to the liner, for the purpose described. 20

11. The mold liner A⁴ provided with the pivoted strip A⁵ projecting beyond its operative end and with the spring A⁹ to hold the strip yieldingly in its normal position.

25 12. The mold liner A⁴ provided with the pivoted strip A⁵ projecting beyond its operative end and formed with the recess A⁸ having its outer wall concentric with the pivotal point of the strip, for the purpose described.

13. The mold liner A⁴ provided with the pivoted strip A⁵ projecting beyond its operative end and formed with the recess A⁸ and having a spring A⁹ located within the recess and bearing against the outer end of the strip A⁵ to hold it yieldingly in normal position, the said recess A⁸ having its outer wall curved to permit the pivotal movement of the strip. 3

14. A slotted mold provided with a strip or member projecting into and extending longitudinally of the mold slot and only partially filling the same at the front, the said member being removable at will and replaceable by another of different length, for the purpose described. 4

15. A mold liner having one end designed to constitute an end wall of a mold and provided with a longitudinal strip projecting beyond said end, said strip being detachably connected to the liner so as to be replaced by another of different length. 5

In testimony whereof, I have affixed my signature in presence of two witnesses.
